(54) **HYDRANTS**

(76) Inventor: **Sater T. Walker**

Plat. 21. Wm. H. Jr.

The schedule referred to in the Letters Patent are making part of the same, containing a description in the words of the said S. Walker himself, of his improvement in the Hydrant for drawing water.

To all whom these presents shall come, &c. &c. Known, That I, S. Walker, of the city & county of Baltimore, State of Maryland, have invented, a new improvement in "the Hydrant for drawing water" which improvement I have a Letters patent under date of the twenty sixth of November, in the year eighteen hundred and thirty four, am that the following is a full and exact description of the construction & operation of the said improvement as invented by me. The said invention consists of an iron case, which will be usually cast, in order to determine the walls so as to afford them the requisite protection. It is also, provided for the purpose of maintaining the distance between the upper and lower ends of the work, that they should be separated by a cast iron case. The ascending tubes from the supply pipes, from which the water is discharged, is usually supported by means of a iron cast iron case, with openings in one or more of its sides, at the base near its bottom, for the purpose of approaching the ends at the lower line, whenever it may be requisite to do, for suspending the water-
seats or cocks. The spear or shaft described in my former patent, as passing down from the top of the Hydrant to the valve seat, has a screw on its upper end, which passes into a through a nut plate, to the covering applied to the upper end of the cast iron case, when on turning the spear, as usual, the valve is raised or closed, I raise the metal cock, when that is raised, within the opening in the cast iron case under ground, and turn off the water according to my first plan. When I have the lining of some pliable substance, in the cork and in the valve seat, I generally put on leather saturated, with beeswax, and apply it to the Hydrant, or the plug ready, by attaching it firmly to the body or plug of the cock. When I use the metal cock upon an enlarged scale for the use of the fire plugs and others, to operate it within the cast iron case, I make the discharging end of

the cock to turn upwards within the body of the case, and from whence to this, so as to receive the spigot end of the ascending pipe to which I attach one or more nozzles for the discharging of the water by, so as to be able to attach one or more hoses to the same plug, or for the purpose of having a convenient mode of attachment at or near the surface of the ground, it also answers in this case to increase the head of water, and removes the possibility of obstruction of the flow of water, from a severer pressure than might otherwise be in the pipe when elevated. To the other end of the cock I form a bell end and am units it to the supply pipe by a circular pipe intended for the purpose of running the front of the case, and the discharging pipe, so as to discharge the water in the same direction in the reverse, front. I use the coupling joints for connecting the pipes, as in my old patent, for the purpose of affording a ready means of detaching them from the cock or valve seat. To preserve at all times the same distance between the upper and lower ends of the works, to prevent separation by frost or other circumstances, as before stated, the cock or valve seat, is placed in the opening in the lower end of the iron case, and the nut plate, or covering in which the gear or shaft works, which is used for raising the valve, & having the one way for turning the plug of the cock, has a screw cut in it, & receives into it the iron on the upper end of the pipe, where the cover is attached. What I claim as my invention, and for which I am ask Letters Patent, is the construction and use of a cast iron case, for the purpose of maintaining the distances aforesaid, either, with or without the wooden log. Also the iron case for protecting the other works of the telescope, in the plug, from injuries. But when it is used as a covering, it is plain against the other works without the connection for maintaining the distances. Also the covering cover of the top by means of screw bolts and nuts, in order to assist in casting and lightening the works. Likewise for adding nozzles or mouth pieces to the discharging pipes for the purpose before mentioned, in describing the fire plug. Also for the manner of using a circular pipe to the fire plug for running the nozzle, or front of the discharging pipe, & case.
